UNITED STATES PATENT OFFICE.

MELVIN SOLOMON GROH, OF TORONTO, ONTARIO, CANADA, AND JOSEPH A. HALLS, OF YOUNGSTOWN, OHIO, ASSIGNEES, BY MESNE ASSIGNMENTS, TO TRUSCON STEEL COMPANY, OF YOUNGSTOWN, OHIO, A CORPORATION OF MICHIGAN.

MACHINE FOR EXPANDING METAL SHEETS.

Application filed August 12, 1924. Serial No. 731,634.

This invention relates to the subject of expanding preslotted metal sheets to produce metal lath and equivalent expanded metal products, generally used in building construction, and primarily has for its object a machine of maximum simplicity as compared with machines now in general use for fabricating the same product.

The machinery usually employed for opening and expanding slotted metal sheets is quite complicated and expensive because of the numerous parts involved and the necessities of adjustments required so that the machine will engage and act upon the individual strands formed by the slits. The present invention is intended to accomplish the desired result with a machine of very simple construction, and of a comparatively few working parts, so that the expense of building and maintaining such a machine shall be very much less than the expense of building and maintaining the machines in general use for expanding slotted metal sheets. Furthermore, it is the purpose of the present invention to provide an expanding machine having the means and capacity for evenly and accurately expanding a slotted metal sheet for its full length, and width.

Another object of the invention is to provide an expanding machine which may satisfactorily be used in connection with a slotted metal sheet which has previously been corrugated, in order that the operation of opening and expanding the metal sheet may be carried on evenly and without buckling and without imposing excessive stretching strains on the individual strands at the sides of the slits.

With these and other objects in view which will more readily appear as the nature of the invention is better understood, the same consists in the novel construction, and combination of parts hereinafter more particularly referred to, illustrated and claimed.

The primary features of the invention are disclosed in my pending application for Patent Serial No. 677,262 filed November 27, 1923 and the present case involves important structural improvements, contributing materially to the efficiency of the machine. It will be understood, that the machine of the present invention is susceptible

of structural modification without departing from the spirit or sacrificing any of the advantages of the invention, but a preferred and practical embodiment of the invention is shown in the accompanying drawings, in which:

Figure 1 is a vertical central cross-sectional view of a drum type expanding machine embodying the improvements contemplated by the present invention.

Figure 2 is an enlarged detail view of the main operating unit of the machine, showing more clearly by enlargement the operative relation between the expanding drum, the stationary tool steel die block, and the holding-down pressure block.

Figure 3 is a top diagrammatic plan view of a form of corrugated slotted blank which may be expanded in the machine.

Figure 4 is an edge view of the form of the blank shown in Fig. 3.

Figure 5 is a side elevation of the machine from its feeding-in side, partly broken away to more clearly illustrate the novel frame construction of the machine.

Figure 6 is a detail elevation of the novel table frame unit which provides the feeding table for the slotted sheets as well as for the adjustable support of the stationary die block.

Figure 7 is an end view of the machine.

Figure 8 is a top plan view of the machine at one end portion thereof.

Figure 9 is a plan view partly in section of the sectional expanding drum or roll showing its unit by unit formation and the spiral set given to the different collar units.

Figure 10 is a vertical cross-sectional view of the expanding roll through one of its collar units for instance on the line 10-10 of Figure 9.

Figure 11 is an enlarged detailed longitudinal sectional view of a portion of the sectional expanding drum showing more clearly the detailed construction of each of the collar units and the manner of keying it on the body roll.

Like references designate corresponding parts throughout the several figures of the drawings.

The distinctive feature of the present invention resides in an operating unit of extreme simplicity and efficiency. That oper-

ating unit primarily includes an expanding drum designated generally by the reference letter A and a stationary die block B arranged in proximal relation to the ribbed periphery of the drum and presenting at an upper corner an anvil edge, b over which the strands of the slitted material are depressed, which provides for the opening of the material. The said expanding unit also 10 preferably includes a pressure bar C arranged parallel with the stationary die block B and in the vertical plane thereof to act as a guide and holding-down element for the slitted sheet, providing means for guiding said sheet into the die pass c and also firmly holding the sheet in such pass while the ribs of the drum engage uncut portions of the sheet.

The entire operating unit comprising the 20 drum A, the die block B and the pressure bar C is supported by a frame-work specially designed to resist undue vibration, and to so brace and support the stationary die block throughout its entire length as to obviate the possibility of such die block having any downward or inward deflection, at 25 any point, that might interfere with the uniformity of the operation of evenly opening a single row of the strands at one time 30 throughout the entire length of the slitted sheet. This novel frame-work includes in its organization the opposite upright frame end stands 1—1 which preferably are rigidly connected together by a structural base 35 frame 2 which operates as a distance rail to separate the frame end stands a proper distance apart, according to the length of the expanding roll which length is determined by the length of the sheet to be operated 40 upon by the machine. The said combined base frame and distance rail 2 is preferably of I-beam formation in cross section in order to obtain all of the structural strength 45 of a beam or girder of that form, the same including the upright longitudinal web 3 and the upper and lower oppositely projecting flanges 4 which provide the I-beam; and, in addition thereto the said structural base frame is preferably provided upon both 50 sides thereof at suitable intervals with the upright stiffening flanges 5 as may be clearly seen from Figs. 1 and 2 of the drawings. The stiffening flanges 5^a at the ends of the structural base frame 2 serve as bolting flanges to receive the clamping bolts 6 extending through bolt openings in such flanges and through corresponding bolt openings in the frame end stands 1—1, thereby completing a skeleton frame structure 55 entirely adequate for carrying and supporting the working parts of the machine. The structural base frame 2 is fitted in place between the opposite frame end stands 1—1 at a distance below the upper ends of 60 said stands in order to leave a space between

the upper portions of the frame end stands, and above the base frame 2, for the mounting of the adjustable table frame-unit 7. This frame-unit is an important feature of the invention as it provides a strong and substantial support and carrier for the stationary die block B as well as a feeding table over which the slitted sheets are fed in any suitable manner to the die pass c of the operating unit. As seen particularly in 75 Figs. 1, 5 and 6, of the drawings the table frame-unit 7 is of a truss or girder formation. It includes a flanged top chord 8 extending longitudinally of the frame unit the full length thereof, and the oppositely inclined flanged bottom chords 9—9 which connect with the vertical end legs 10 of the frame unit 7, and incline inwardly and downwardly from such end legs to a lower plane where they join with a central bearing 85 saddle or foot 11 having a flat bottom seating surface 12 which has a firm bearing engagement with the upper flat central bearing seat 13 formed at the center and upper side of the bottom structural base frame 2 of the frame. The end portions or legs 10 of the frame unit 7 are provided at their bottom portions with the terminal bearing feet 14 which have a flat bearing engagement with the upper bearing seats of the bearing 90 shoulders 16 which project inwardly from the frame end stands 1—1 at a point above the base frame 2. Thus, it will be seen that the table frame unit 7 has a three-point support with a deep girder formation at the center, thus presenting the form of a bridge girder, and bringing the strength and advantages of such a girder into a unit designed preferably to support a stationary die block, and to resist all strains and shocks 95 which are imposed on that die block in the 100 expanding operation.

The table frame unit 7 above described is adjustably mounted in order to provide the 110 finest adjustment desired or required for the stationary die block B. For that purpose it will be seen that the fastening bolts 17 which connect the end portions of the frame unit 7 with the supporting shoulders 16 of the end stands pass through slotted holes 18 115 which admit, when said bolts 17 are loosened, of adjustment of the frame unit 7 toward and from the expanding roll 8, this adjustment being made through the medium of adjusting screw-bolts 19 mounted in the bolt lugs 20 provided at the tops of the end frames 1—1, the inner ends of said screw-bolts 19 engaging as at 21 with the table-top part 22 of the said frame unit. Jam nuts 23 upon opposite sides of the bolt lugs 20 120 provide for locking the screw-bolts 19 against movement, after proper adjustment has been made. Likewise the fastening bolts 17 are tightened after proper adjustment has 125 been made.

It will be observed that the adjustable table frame unit 7 preferably is a single piece casting, and the upper part thereof is formed with the flat table-top portion 22 upon which the slotted sheets are placed and fed through the die pass to the operating unit, and at its inner edge adjacent the expanding roll the frame unit 2 is provided therein with an angular mortise 25 forming a receiving recess for the stationary die block B and providing a solid seat or base upon which it rests; also, a solid back against which it rests, both of which features is important in the mounting of a die block 5 upon the frame unit 7. The receiving recess 25 is subject to the shocks of an operation such as takes place in the present machine. Upon wear in itself or in the cooperating elements of the operating unit which might require a vertical adjustment of the die block B, such adjustment is provided for by adjusting screw-bolts 26 extending through vertically arranged slots 27 formed in the top part of the table frame unit 7, the threaded ends of said bolts engaging threaded sockets 28 in the die block B. The loosening and tightening of the bolts 26 will permit of slight vertical adjustment of the stationary die block, and, as indicated by the dotted line in Fig. 1 of the drawings, a thin metal 15 shim or shims may be interposed between the seat 25 and the bottom of the die block so that the solid bottom seat for the latter may be maintained under all conditions.

The holding-down pressure bar C of the operating unit may be conveniently supported in its operative position from the angular upstanding supporting brackets 28 surmounting and mounted upon the frame end stands 1-1. The upstanding members 29 of the said brackets are provided with the slotted holes 30 which receive the screw bolts 31 engaging threaded openings in the pressure bar C, the loosening of said bolts 31 permitting of the vertical adjustment of the pressure bar C to vary the width of the die pass c, according to the requirements of the slotted sheet. This vertical adjustment of the pressure bar C is accomplished by the adjusting screws 32 working through 40 threaded openings 33 in overhanging top flanges 34 of the brackets 28 and engaging threaded openings 35 in the end portions of the pressure bar. Lock nuts 36 are preferably associated with the adjusting screws 32 to hold the adjustment.

A detail of practical importance in connection with the pressure bar C is the particular construction of the active end thereof. That is to say, the pressure bar is provided at one side of its bottom edge portion with an inclined guide face 36 which provides a flaring opening through which the edge of the slotted sheet may be inserted for guiding into the pass c. At the side opposite the inclined guide face 36 the face of the

pressure bar C is curved as at 37 preferably on the same arc of a circle with the curved guiding face 38 on the stationary die block B. The said curved faces 37 and 38 are substantially concentric with the ribbed periphery of the expanding roll A, permitting the ribs thereof to pass in very close proximity to the anvil edge b of the die block, the curved part 38 of the die block serving to facilitate the downward deflection of the expanded portion of the sheet, as fast as the expansion takes place.

The structural formation of the expanding drum A is an important part of the invention not only from a manufacturing standpoint, but also from the standpoint of contributing materially to the commercial success of the machine. Referring thereto it will be seen particularly by reference to the group of Figs. 9, 10 and 11 that the expanding drum primarily includes a body roll 39 provided at its ends with the journals or gudgeons 40 journaled in suitable bearings 41 provided in the end stands of the frame. This body roll is substantially coextensive in length with the length of the sheet to be expanded and is preferably designed to have assembled thereon a number of similar ribbed collar units 42.

Each of the collar units 42 comprises a cylindrical body portion 43 provided with the inwardly projecting end flanges 44 adapted to receive the keys 45 engaging the longitudinal keyway 46 in the body roll 39. The said body portion 43 of each collar unit may consist of a casting and affords a base upon which is fitted by rivets 47, or otherwise, a tool-steel or equivalent shell 48 in which are cut the longitudinally extending die ribs 49. The die ribs 49 are cut upon each collar unit in saw-tooth formation, and cover the entire periphery of the collar unit excepting at one point in its circumference where the said ribs are preferably interrupted as at 50, producing at that point a land or wide plain space. This is intended, when the roll is at rest in its starting position, to receive the edge of the slotted blank, thereby to position the first row of strands for engagement by the first rib of the expanding drum when the rotation of the latter is started.

The ribbed collar units 43 are assembled in close side-by-side relation upon the body roll 39, and are held secure in their assembled positions by the fastening ring-nuts 51 mounted on threaded end portions 52 of the body roll 39. When thus assembled, an expanding drum is produced in which the die-ribs may be said to extend continuously in straight lines longitudinally of the whole drum, from end to end thereof, so that each rib of the drum, made up by the rib sections on the collar units, will present a substantially continuous flat shoulder that engages

an entire row of strands, and will provide for depressing all of said strands at once over and below the anvil edge *b* of the die block *B*. The dotted lines in Fig. 3 of the drawings indicate the continuous die-rib in its active relation to a single row of strands which are engaged by the die-rib in its downward movement, and in Fig. 4 the dotted line shows the initial engagement of a die-rib with the crests or zeniths of the upstanding corrugations of a corrugated sheet when a sheet of that form is employed, regardless of the position of the bonds or keys between the strands in separate rows.

It will be seen from Figs. 9 and 11 of the drawings that when the collar units 42 are assembled there is a slight groove left between the ends of contiguous ribs, and the said grooves receive the ends of wires or equivalent stripper elements 64 extending upward to a point just below the active edge of the block *B*, and downward to a point well below the drum. These elements function to assist in stripping or freeing the expanded mesh from the ribbed drum as the fabric is drawn downward by the latter. Also, a box-like roll guard 65 is arranged adjacent the outer exposed side of the drum and the stripper elements may conveniently be supported therefrom, as shown.

In connection with what has been termed the longitudinally extending die-ribs a slight spiral set may be given to such ribs, by giving a slight spiral set to the keyway 46 in the body roll 39, as may be seen by comparing the said keyway with the roll center line indicated in Fig. 9 of the drawings. Such set is so slight as not to interfere with using straight keys for fastening the collar units to the roll body, not disturbing the longitudinal continuity of each die-rib and the substantially continuous shoulder thereof. The effect of this slight spiral setting of the die-ribs is to ease the shock of a rib engaging a whole row or line of strands substantially at the same time.

Any suitable gearing appliances may be employed for intermittently rotating the expanding roll, one revolution at a time, that is, providing for its continuous rotation through one revolution to expand a slotted metal sheet of a given length and width, the automatic stopping of its motion when thus revolved one revolution, and then starting the same to take up the expansion of the second sheet. However, for illustrative purposes there is shown in the drawings one way of doing that. In such illustration the expanding drum shaft is shown fitted with the spur gear 53 meshing with an intermediate gear unit 54, interposed between the same and a driving pinion 55 on the drive shaft 56 which carries the belt or power pulleys 57. Associated with these instrumentalities is a clutch-device 58 having a trip lever 59 carry-

ing a trip element 60 adapted to be engaged by a trip detent on the spur gear 53. The said detent, at the completion of one revolution of the expanding drum, engages the trip element 60 of the lever 59, causing the latter to move in a direction to disengage the clutch, thereby automatically stopping the rotation of the drum. When another slotted sheet is inserted, and its inside edge entered into the land 50 of the expanding drum, the machine is again started by manipulating the starting lever 62 having an operating connection 63 with the clutch 58 so as to provide for re-engaging the clutch. This operation is repeated while the machine is at work.

Reference has been made herein to the use of a corrugated slotted metal sheet to illustrate one kind of a sheet that may be opened into meshes by the machine. A sheet of that description has been found satisfactory for the practical and commercial operation of the machine. The corrugations not only compensate for shortening of the sheet due to the expanding operation, but also serve to stiffen the structure and present the strands to the die-teeth of the drum in a way that any tendency of the pressure or strain on the strands to buckle or deflect the sheet is effectually and stoutly resisted. This is due to the fact that the corrugations are presented endwise to the continuous ribs of the expanding drum, and the latter engage first the upstanding crowns or apexes of the corrugations. In that particular the present invention provides a new way of opening or expanding a preslotted metal sheet by a drum-type expanding die and necessarily is applicable to a pre-slotted sheet of either plain or corrugated form.

From the foregoing it is thought that the construction, operation and many advantages of the herein described expanding machine will now be apparent without further description, and, it will be understood that changes in the form, proportion and minor details of construction may be resorted to without departing from the principle or sacrificing any of the advantages of the invention.

I claim:—

1. An expanding machine for pre-slotted metal sheets including a stationary frame member having a die seat, a stationary die block seated therein, a pressure bar arranged directly above the die block, and a ribbed expanding drum supported to rotate in proximity to the die pass between said block and bar, said ribs having non-cutting substantially continuous longitudinal shoulders operating on a longitudinal portion of the sheet parallel to the edge of the sheet.
2. An expanding machine for slotted sheets including a frame-work, a stationary frame unit having a three-point support

- within the frame-work, a die block carried by the frame unit, and a rotating ribbed expanding drum.
3. An expanding machine for slotted sheets including a frame-work comprising end stands and a base frame, a frame unit having a support respectively on the base frame and on said end stands, a die block carried by the frame unit, and a rotating ribbed expanding drum.
4. An expanding machine for slotted sheets including a frame-work comprising upright end stands, a base frame, and a frame unit having a center bearing support on said base frame and end bearing support on said base stands, a die block fitted to the frame unit, and a rotating ribbed expanding drum.
5. An expanding machine for slotted sheets including a frame-work comprising end stands, a base frame between and connecting said stands, and an adjustable frame unit having a bearing support at the center on said base frame and at its ends on said end stands, a die block fitted to the frame unit, and a ribbed expanding drum.
6. An expanding machine for slotted sheets including a frame-work comprising end stands, a base frame connecting said stands, and a frame-unit having a center bearing support on the base frame and end bearing supports on the end stands, the latter bearing support being at a higher elevation than the center bearing support, a die block fitted to the frame unit, and a ribbed expanding drum.
7. An expanding machine for slotted sheets including a frame-work comprising end stands having inwardly projecting supporting shoulders, a base frame connecting said stands, and a table frame unit having a center bearing support on the base frame and end bearing supports on said shoulders, the latter being at a higher elevation than said center bearing support, a die block fitted to the frame unit, and a ribbed expanding drum.
8. An expanding machine for slotted sheets including a frame-work comprising end stands, a base frame connecting said stands, and an adjustable frame unit consisting of a truss-frame provided with a deep central portion having a bearing support on said base frame and relatively narrow end portions having bearing supports on said end stands, a die block fitted to the frame unit, and a ribbed expanding drum.
9. An expanding machine for slotted sheets including a frame-work comprising upright end stands, a structural base frame connecting said stands, and a frame unit slidably supported on the base frame and on said end stands and provided with a table top portion and with a die seat, a die block adjustably mounted in said seat, adjusting means for said frame unit, and a ribbed expanding drum.
10. An expanding machine for slotted sheets including a frame-work comprising upright end stands, a table frame unit adjustably mounted between said stands, a die block fitted to said frame unit, upright supporting brackets on said end stands, a pressure bar adjustably mounted in said brackets and arranged within the vertical plane of said die block, and a rotatable ribbed expanding drum.
11. A machine including a frame member carrying a stationary die, and a ribbed expanding drum having its ribs spirally set.
12. A machine including a frame member carrying a stationary die, and an expanding drum comprising a plurality of ribbed collar units disposed to give a spiral set to the ribs extending longitudinally of the drum unit.
13. A machine including a frame member carrying a stationary die, and an expanding drum comprising a body roll, and a plurality of individual ribbed collar units assembled in side by side relation upon said body roll, and stripper wires arranged between the contiguous ends of the ribs of adjoining collar units.
14. A machine including a frame member carrying a stationary die, and an expanding drum comprising a body roll, and a plurality of roll units assembled in side-by-side relation on the body roll, each collar unit consisting of a body member keyed to the body roll and provided with a steel shell having die ribs in saw tooth formation.
15. A machine including a frame member carrying a stationary die, and an expanding drum comprising a plurality of individual ribbed units arranged in side by side relation and having the ribs interrupted at one point in the circumference thereof to provide a land extending longitudinally of the drum.

In testimony whereof we hereunto affix our signatures.

MELVIN SOLOMON GROH.
JOS. A. HALLS.
